UNITED STATES PATENT OFFICE.

ANDREW R. RIDDERSTROM, OF NAHANT, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

SKIVING MACHINE.

Application filed February 11, 1924. Serial No. 692,167.

The present invention relates to skiving machines, and more particularly to machines, in which a shoe upper or other sheet material is advanced by a feed roll and a feed 5 disk to a rotating skiving knife which cuts a scarf in the margin of the material.

An object of the invention is to provide an improved deflector for the chips which are cut from the material.

10 A further object is to provide an improved deflector for the body of the material.

A further object is to provide an improved knife guard.

15 A further object is to provide an improved guard for protecting the operative parts of the machine from the effects of dust and the like.

20 Another object is to provide an improved guard for protecting the operator from oil or other particles that might be spattered by centrifugal action during the operation of the machine.

25 Still another object is to provide an improved guard for preventing the operator from coming into contact with other moving parts of the machine.

Other and further objects will be explained hereinafter and will be particularly 30 pointed out in the appended claims.

35 In the accompanying drawings, Fig. 1 is a longitudinal, central, vertical section of a skiving machine embodying the present invention in its preferred form; Fig. 2 is a detail elevation, about half way between a front elevation and a side elevation, parts 40 of the machine, as the feed disk, being removed, and other parts broken away, for clearness; Fig. 3 is a section taken upon the line 3—3 of Fig. 2, looking in the direction of the arrows; and Fig. 4 is a section taken upon the line 4—4 of Fig. 2, looking in the direction of the arrows.

The invention is for illustrative purposes shown in the accompanying drawings as embodied in a machine having many features in common with a machine constituting the subject matter of a copending application, Serial No. 521,239, filed December 9, 1921. The frame of the machine is provided 45 with an overhanging arm or head 22 that carries a disk-shaped skiving knife 185 and a feed disk 143. The feed disk cooperates with a feed roll 95 to feed material to the knife. The customary presser foot has been

omitted from the drawings in order not to 55 complicate the disclosure unnecessarily. A projection or lug 26, provided with a main bearing 27, is fastened to the front end of the head 22 by screws 28. A shaft 32 is journaled in the bearing 27. The feed roll 60 and the feed disk are driven from the shaft 32, as is explained more fully in the above-identified application. The feed-roll driving mechanism is not illustrated herein. The feed disk is driven from a worm 135 that is 65 secured to the shaft 32 and that meshes with a worm gear 136 that is keyed or bolted to the upper end of the feed-disk shaft 137. The shaft 137 is journaled in an adjustable bearing 140. The bearing may be adjusted 70 by means of a thumb nut 251, as is fully described in a copending application Serial No. 684,437, filed January 4, 1924. The feed disk 143 normally presents an angular working relation with respect to the feed roll 95, 75 and the driving gearing is such that both axial and transverse movement may be had between the gears without disengagement thereof, either for adjustments or when performing work, the teeth of the gear 136 80 merely slipping through the teeth of the worm 135.

The knife 185 is carried in a bracket 170 that is angularly adjustable about a rod 164 so as to provide for skiving scarfs of different angles in the margin of the material. The angular adjustment may be effected through a finger or lug 188 that projects from the knife bracket 170, and that is yieldingly engaged by a dog 17 through the 85 action of a spring 189. The spring 189 thus tends to maintain the lug 188 in engagement with a limiting stop 190. The position of the stop 190 may be adjusted by an adjusting screw 191 that is tapped in the head 22 of 90 the machine and that engages a shoulder (not shown) of the stop 190. Adjustment of the screw 191 will therefore result in rotatably adjusting the angular position of the knife bracket 170 and the knife 185 that is mounted 95 thereon, the spring 189 acting always to maintain the lug 188 in engagement with the adjustable stop 190. This adjustment, which is fully explained in the above-entitled application, is not further illustrated herein, 100 because not necessary to an understanding of the present invention.

The knife is directly driven from a belt 1,

acting on a pulley 4, and exerting a force upon the knife shaft in the same angular direction as the spring 189. The upper end of the knife shaft is provided with a worm 182. 5 This worm meshes with the worm portion of an elongated pinion 163 that is freely rotatable upon the stationary rod 164. The worm portion of the pinion 163, with which the worm 182 meshes, is at the rear of this pinion. 10 The pinions 163 and 182 are maintained in meshing engagement, irrespective of the angularly adjusted position of the bracket 170 and the skiving knife 185 that is carried thereby. The front portion of the pinion 163 constitutes a spiral gear that 15 meshes with a spiral gear 162, shown to the right of the feed-shaft bearing 27 in Fig. 1. The gear 162 is mounted upon a hollow shaft 2 through which the feed shaft 32 extends. 20 The hollow shaft is freely rotatable with respect to the feed shaft 32, but the two shafts are adapted to be clutched together, to rotate as a unit, as described in the above-identified application, Serial No. 521,239. 25 The foregoing brief description of the machine of the aforementioned applications will suffice as a setting for the features of novelty that are now to be explained, and it will be understood that the said features of 30 novelty are not restricted to any particular machine, the machine of the said applications being chosen for illustrative purposes only, to make clearer the description that is now to follow. 35 A member 51 is secured by screws 53 or the like to the knife bracket 170. The member 51 depends towards the knife 185, and is provided with an opening 55 through which the pulley 4 projects. The member 51 is 40 provided with two ears 57 and 59 that curve part way around the pulley 4, on both sides of the opening 55. A guard 61 is secured to the ear 59 in any desired manner, as by means of screws 63. The guard 61 curves 45 around the pulley 4, at 65, and extends back at 67 to cover a large portion of the belt, so as to protect the operator from contact with the pulley and the belt. A knife guard 69 is secured by screws 71 to the lower portion 50 of the member 51. Slots 75 in the knife guard 69, through which the screws 71 extend permit adjustment of the knife guard. A deflector 77 is shown secured to the ear 59 of the member 51 by the same screws 63 that 55 hold the guard 61, and serves to deflect upward and outward the chips 79 as they are cut from the body 81 of the material by the knife 185, as is illustrated in Fig. 2. The body 81 of the material is deflected downward, away from the operating instrumentalities of the machine, by a deflector 83 that is secured to the knife guard 69, by a screw or the like 85, in position beyond the feed roll 95 in the line of feed. A pin 87, 60 that is rigid with either the knife guard 69 65

or the deflector 83, passes through an opening in the other of the said two members to prevent accidental turning movement of the deflector 83 about the screw 85.

The oil that surrounds the knife shaft 70 has a tendency to leak to the bottom of the shaft when the machine is idle, and to spatter outward, by centrifugal action, when the machine is again started. This is very 75 disagreeable to the operator who is subjected to this oil spattering. The knife guard 69 and the deflector 77 are positioned so as to receive the oil so scattered, thus 80 eliminating this disagreeable feature. The knife guard 69 and the deflector 77 serve also as a dust protector for the knife shaft and the parts contiguous thereto.

The description of many portions of the machine an understanding of which is not 85 essential to an understanding of the present invention has purposely been omitted, and many parts of the machine have purposely not been illustrated in order not to distract the attention from the features of essential 90 novelty. Fuller explanation of such portions of the machine will be found in the copending applications referred to above. It will be clear that the features of novelty 95 may be embodied in other machines, and in machines of other types, and that modifications may be made therein by persons skilled in the art, without departing from the spirit and scope of the invention, as defined in the appended claims.

What is claimed is:

1. A machine of the class described having, in combination, a rotary knife, means for rotating the knife, the knife being constructed and arranged to cut material at a predetermined position in the line of feed, 100 means for feeding the material to the predetermined position so as to be cut by the knife, and a deflector extending a substantial distance beyond the predetermined position in the line of feed in a direction 105 at a substantial angle to the plane of rotation of the knife for positively deflecting the body of the material a substantial distance away from the knife in a direction at a substantial angle to the plane of rotation 110 of the knife after the material has been fed beyond the feeding means and a chip has been cut therefrom.

2. A machine of the class described having, in combination, a knife, means for feeding material to the knife, a guard for the knife, and a deflector carried by the guard extending a substantial distance beyond the feeding means in the line of feed for deflecting the body of the material away from the 115 knife after a chip has been cut therefrom by the knife.

3. A skiving machine having, in combination, a rotary knife, means for rotating the knife, the knife being constructed and 120

130

arranged to cut material at a predetermined position in the line of feed, a feed roll and a feed disk for feeding the material to the predetermined position so as to be cut by the 5 knife, and a deflector extending a substantial distance beyond the predetermined position in the line of feed in a direction at a substantial angle to the plane of rotation of the knife for positively deflecting the 10 body of the material a substantial distance away from the knife in a direction at a substantial angle to the plane of rotation of the knife after the material has been fed beyond the predetermined position and a 15 chip has been cut therefrom by the knife.

4. A skiving machine having, in combination, a knife, means for feeding material to the knife, means for driving the knife, a supporting member, a guard for the driving 20 means supported by the member, and a deflector for deflecting the chips cut from the material carried by the member.

5. A machine of the class described having, in combination, a rotary knife, means 25 for rotating the knife, the knife being constructed and arranged to cut the material at a predetermined position in the line of feed, means for feeding the material to the 30 knife, a deflector on one side of the plane of rotation of the knife extending a substantial distance beyond the predetermined position in the line of feed in a direction at a substantial angle to the plane 35 of rotation of the knife for positively deflecting the body of the material on the said one side of the plane of rotation of the knife a substantial distance away from the knife in a direction at a substantial angle 40 to the plane of rotation of the knife after the material has been fed beyond the feeding means and a chip has been cut therefrom, and a deflector on the other side of the plane of rotation of the knife extending 45 in a direction at a substantial angle to the plane of rotation of the knife for deflecting the chips cut from the material on the said other side of the plane of rotation of the knife a substantial distance away from the 50 knife in a direction at a substantial angle to the plane of rotation of the knife.

6. A skiving machine having, in combination, a knife, means for feeding material to the knife, a supporting member having 55 two ears, a deflector for deflecting the chips

cut from the material carried by one of the ears, and a deflector for deflecting the body of the material carried by the other ear.

7. A skiving machine having, in combination, an oil-covered shaft having a skiving knife for skiving the margin of sheet material, means for rotating the shaft, a feed roll and a feed disk for feeding the material to the knife, a guard for the knife, and 60 a deflector for deflecting the chips cut from the material, the guard and the deflector being constructed and arranged to receive the oil as it is spattered outward, by centrifugal action, during the rotation of the 65 shaft.

8. A skiving machine having, in combination, a knife bracket, a knife carried by the bracket, a feed roll and a feed disk for feeding material to the knife, a deflector for 70 deflecting the chips cut from the material carried by the bracket, a guard for the knife carried by the bracket, a deflector for deflecting the body of the material carried by the knife guard, and means for adjusting the bracket, the knife, the deflectors and the guard as a unit.

9. A skiving machine having, in combination, a knife, a feed roll and a feed disk for feeding material to the knife, a pulley for 85 driving the knife, a belt for driving the pulley, a supporting member having an opening through which the pulley projects and two ears on both sides of the opening, a guard for the belt secured to one 90 of the ears, a deflector for deflecting the chips cut from the material secured to the said one ear, a guard for the knife secured to the other ear, and a deflector for deflecting the body of the material secured to the 95 knife guard.

10. A skiving machine having, in combination, a shaft having a skiving knife for skiving the margin of sheet material, means for rotating the shaft, a feed roll 100 and a feed disk for feeding the material to the knife, a guard for the knife, and a deflector for deflecting the chips cut from the material, the guard and the deflector being constructed and arranged to 105 protect the shaft against dust.

In testimony whereof, I have hereunto subscribed my name this 9th day of February, 1924.

ANDREW R. RIDDERSTROM.
